VOLTAGE-TUNEABLE MAGNETRON

Horst W. A. Gerlach, Bethesda, Md., assignor to the United States of America as represented by the Secretary of the Army

Filed Dec. 21, 1961, Ser. No. 161,321

4 Claims. (Cl. 315—39.55)

(Granted under Title 35, U.S. Code (1952), sec. 266)

The invention described herein may be manufactured and used by or for the Government for governmental purposes without the payment to me of any royalty thereon.

This invention relates to microwave signal sources and especially to improvements in magnetrons.

One well known type of voltage tuneable magnetron has an anode formed by a single pair of interdigital finger elements representing, together with the sole, its R-F interaction space. An annular beam of electrons is injected from one end into the interaction space. These electrons are rotated by means of the combination of a radial electric field and an applied magnetic field. However, because of the injection the motion of the electrons is not entirely azimuthal, a component of electron velocity v_z being directed along the longitudinal axis of the anode fingers. In prior magnetrons of this type, even the lowest axial or longitudinal electron velocity v_z attainable is large enough to seriously restrict the time of interaction of the beam with the R-F signal wave. As a result, the amount of output power available is unduly limited. Attempts to increase anode efficiency and output power by lengthening the anode fingers meet with little success due to molding difficulties which such measures create. The length of the anode fingers is also limited by other design considerations determining the desired operating frequency.

An object of this invention is to provide a new and improved magnetron.

Another object is to increase the power output of voltage-tunable magnetrons.

A further object is to provide a magnetron oscillator having a uniform level of output power over a wide frequency range.

Still another object of the present invention is to reduce end radiation losses of high power magnetrons.

An additional object is to provide a voltage-tuneable magnetron having improved efficiency as compared with known single interdigital anode magnetrons.

A further object is to improve the coupling between the R-F vanes in the interaction region of a magnetron and its coaxial output line.

The specific nature of the invention, as well as other objects, uses and advantages thereof, will clearly appear from the following description and from the accompanying drawing, in which:

FIG. 1 is a vertical sectional view of a magnetron constructed in accordance with the present invention shown mounted within its external microwave cavity. This cross-section is taken along central axis X-X' of FIGS. 2, 4, 5 and 6.

FIG. 2 is a plan view of the microwave cavity casing which serves to support the magnetron tube, with its top plate and the magnetron tube removed.

FIG. 3 is a sectional view of the casing taken along line 3—3 in FIG. 2.

FIG. 4 is an isometric view of the microwave cavity casing with its top plate in place.

FIG. 5 is a diagram in cross-section of the interdigital anode fingers.

FIG. 6 is an isometric view of one form of the anode fingers according to this invention.

2

FIG. 7 is an alternate embodiment of the anode finger elements.

Referring now in detail to the embodiment of the invention illustrated in FIG. 1, the numeral 10 generally designates a voltage-tuneable magnetron. The various electrodes and other components of the magnetron tube are mounted within a microwave cavity formed by an external casing. The casing includes a base member 11, a center conductor plate 21, and a top plate 28. Base 11 comprises a bottom plate 12, two side walls 13 and 14 (FIGS. 2 and 3), and one end wall 15, whose inner surfaces form boundaries of the aforesaid microwave cavity. End wall 15 has a rectangular groove 16 located in its upper edge, as shown in FIGS. 3 and 4, which receives and supports one end of center plate 21. Bottom plate 12 contains a pair of concentric holes 17 and 18 which provide a large circular opening with a projecting lip 19, as best seen in FIGS. 1 and 3. Center conductor plate 21 is a flat plate of rectangular shape with an L-shaped cross section formed by an upstanding wall at one end, its left end in FIG. 1. Center plate 21 contains an aperture 25 with a projecting lip 26 of slightly larger inside diameter than that of lip 19. A cylindrical conductor 22 slotted at one end and affixed to plate 21, as shown in FIGS. 1 and 2, serves as an output connector for the magnetron. Plate 21 rests in groove 16 at its left end and is spaced from the base 12 at its right end by insulator blocks 23 and 24 (see FIG. 2). The top plate 28 is supported on walls 13, 14, and 15 where it completes the formation of the microwave cavity. A large aperture 29 in top plate 28 is provided with threads 30 and has a projecting lip 31 at its bottom edge. A ring nut 32 in the form of a flat disk has external threads so that it meshes with threads 30 within aperture 29, for a purpose appearing later.

The magnetron tube structure is centrally mounted within apertures 18, 25 and 29 in order to place its R-F circuit inside the microwave cavity. Considering now the internal construction of the magnetron tube, a cylindrical sole 35 maintained at zero R-F potential is held in position by means described subsequently, along the central axis Y-Y' of the microwave cavity. The anode is an interdigital R-F circuit having two axially aligned rings of interleaving fingers, or vanes. This interdigital structure effectively has three terminals, the three conducting discs 37, 39 and 41 serving as the aforementioned terminals. There are three sets of anode fingers 36, 38 and 40 (FIG. 6), each finger extending, respectively, from the inner rim of one of the discs 37, 39 and 41. The fingers, or vanes, are integral extensions of their respective discs, formed at right angles with the disks 37, 39 and 41. Center terminal disc 39 carries the first set of fingers 38 attached thereto at the mid-points of the fingers, as clearly appears in FIGS. 1 and 6. Top disc 37 supports a like number of fingers 36 which project downward in an interleaved fashion between fingers 38. Fingers 40 on the bottom disc 41 extend upward in axial alignment with vanes 36. FIG. 5 illustrates in cross-section the alternation of fingers 38 with the pairs of fingers 36 and 40, proceeding around the inner edge of the terminal discs. The R-F structure 36, 38, 40 is suitably spaced radially to define an interaction region of proper size for the magnetron. Fingers 36 together with the upper halves of the fingers 38 form one interdigital line within the top section of the microwave cavity, while fingers 40 with the lower halves of fingers 38 act as another such line, in the cavity section below center plate 21. These two anode lines are effectively positioned back-to-back within cavity sections which are so tightly coupled together that only a single resonance appears. The result of this novel arrangement is that the axial length of the interaction is substantially increased without lengthening the anode fingers.

A pair of ceramic insulating rings 45 and 46 (FIG. 1) serve as spacing members to hold discs 37, 39 and 41 in their proper positions, as shown. Disc 41 fits inside hole 18 in base 11, seating upon lip 19, while lip 26 similarly supports terminal disc 39. An annular connector 48 of U-shaped cross-section rests within aperture 29, mounted upon lip 31 with its inner rim 49 overlapping disc 37. Connector 48 electrically couples terminal 37 to the microwave cavity casing at 28. The disc 41 being of reduced outside diameter, the tube unit can be inserted from above through aperture 29 into the cavity until discs 39 and 41 abut, respectively, lips 26 and 19. Then connector ring 48 is fitted in place upon lips 31 and disc 37, and aforementioned ring nut 32 is threaded into threads 30 to lock ring 48 and the magnetron tube against axial displacement. The magnetron tube itself further contains a control anode 52 and a cathode 65. Control anode 52 is a disc having an internal depending conical portion 53. Its position relative to sole 35 and the R-F anode is established by a spacing ring 51 similar to insulators 45 and 46. Another ceramic ring 54 resting upon control anode 52 carries a circular metal plate 55 with a small central hole having two counterbores to form a pair of lands therein. A thin walled metal tube 56 has an upper rim 57 fitting the inner land of plate 55 to mount the tube 56 inside the plate hole. An insulating washer 60 seated upon the outer land of plate 55 and on rim 57 supports a member 61 centrally along axis Y-Y'. Member 61 is a cylindrical rod with a reduced end portion 62 and a flat circular head 63 overlapping washer 60. A cathode filament 65 is helically wound in the form of an inverted conical frustum, as illustrated in FIG. 1. At the enlarged upper end, cathode 65 fits tightly over tube 56, the other end of the filament extending inwardly to coil around end 62 of rod 61. The cathode filament 65 is thus disposed symmetrically respecting axis Y-Y' and aligned closely above sole 35, with control anode 52 situated between the cathode and the interaction region. Cathode 65, control anode 52, sole 35, the R-F anode, the spacer rings and the various other internal mounting elements form a unitary structure, which is referred to herein as the magnetron tube.

The opposite end of the magnetron tube comprising the support for sole 35 will now be described. The lower part of sole 35 is of smaller diameter, forming an end rod 35'. A retaining washer 70 of conductive material is force fitted upon the lower extremity of rod 35', where it serves to support another insulating washer 71 and a metallic disk 72 on rod 35'. Disk 72 has a center hole counterbored underneath to receive the upper surface of washer 71. An insulating spacer ring 47 mounted on an upper shoulder of disk 72 abuts terminal disc 41 of the R-F anode. Thus, by axially adjusting end 35' in retaining washer 70, sole 35 is positioned correctly within the magnetron tube and firmly held along axis Y-Y' by members 70, 71, 72 and 47.

A magnetic pole piece 74, shown in cross-section in FIG. 1, is adapted to engage the lower end of the magnetron tube within aperture 17. The upper cylindrical body of pole piece 74 contains a large circular bore 75 with an inner rim or lip 76. A blind hole 77 extends deeper into the center of pole piece 74, the latter also having an external circular shoulder 78.

An insulator 79, an annular member with an outer flange giving it an L-shaped cross section, is placed within hole 17 in plate 12. When pole piece 74 is inserted within member 79 until shoulder 78 contacts the latter, the lip 76 firmly engages disk 72 to hold the pole piece in place. Washer 70 rests on the bottom of bore 75 with 35' extending into hole 77. An insulator 80 identical with member 79 surrounds pole piece 74 on the opposite side of the shoulder 78.

An annular connector 83 of conductive material is provided with a central aperture 84, a projecting lip 85 inside the aperture, and a flared side wall 86 imparting

5 a generally conical shape. This connector serves to apply a suitable D.C. potential to the control anode 52. The diameter of 84 is large enough so that connector 83 may be placed over the magnetron tube until lip 85 tightly grips the periphery of anode 52. A terminal pin 87 facilitates connection of an electrical cable (not shown) for coupling with a D.C. supply.

10 A second magnetic pole piece 90, generally similar to pole 74, is arranged to fit in place over the upper end of the magnetron tube, once the connector 83 has been mounted on anode 52. A bore 91 in the smaller end of member 90 has a rim 92 adapted to engage circular plate 55 of the tube unit. A strong magnetic field directed along axis Y-Y' is established in the gap between pole-pieces 90 and 74, which are composed of high reluctance magnetic material. Any well known type of magnetic field source may be used to apply the field to pole pieces 74 and 90. An additional magnetic insert 94 serves to further direct and concentrate the magnetic field in the interaction region between sole 35 and the R-F anode elements 36, 38, and 40. Member 94 has the form of a thick ring with a depending ridge, the opposite side being affixed to a groove in plate 55.

15 The operation of the magnetron shown in FIGS. 1-6 will now be briefly indicated. (Suitable external electrical connections (not shown) are brought out from plate 55 and rod 61 for coupling cathode filament 65 to a filament power supply.) The cold cathode or sole 35 and filament rod 61 are at zero potential. With a pre-determined positive D.C. voltage applied through connector 83, the injection control anode 52 surrounding emitting cathode 65 serves to focus emitted electrons into a beam which encircles sole 35 and travels toward the lower end disk 72. The electrons follow a helical path which increases in radius, expanding toward the R-F anode in the presence of the magnetic field.

20 As is well known, in voltage tuneable magnetrons, it is necessary to provide an electron beam in which the current is independent of the D.C. voltage variations at the main anode. The injected-beam tubes achieve this condition by controlling beam current with an injection anode, such as control anode 52. Even though the applied voltage of the R-F structures 36, 38, 40 is large, anode 52 shields the cathode from the electric D.C. field due to its position in proximity to the cathode 65. Thus, the potential of control anode 52 determines the operating point of emitting cathode 65 of the "temperature limited" characteristic. Constant beam current is assured even with variations of the voltage of the inter-digital structure, thus allowing voltage tuning of the operating frequency.

25 An important feature provided in accordance with this invention, is the particular conical configuration imparted to emitting cathode 65. It has been discovered that this filament shape, combined with the focussing of control anode 52, 53 and magnetic insert 94 gives a nearly uniform current distribution along the cathode surface. That is, with an optimum "cathode angle" of the filament 65, uniform cathode loading is obtained. That is not true in prior art cylindrically wound cathode filaments of constant radius, whereby the portion next to the anode structure is more heavily loaded and a non-uniform cathode loading results.

30 As the electrons move radially outward from sole 35, they are restarted by the induced R-F fields in interdigital fingers 36, 38, 40 and, on the average, transfer energy to the R-F fields to sustain them. Since both fingers 40 and 36 are electrically connected to the ground plane of the microwave cavity casing 11, and since these fingers are short in comparison with the operational R-F wavelength, the top and bottom terminal discs 37 and 41 are at the same R-F potential. The center disc 39 is 180° out of phase with the other discs. As a result, π -mode operation occurs in the magnetron, with alternate vanes 36, 38 and 40 being separated electrically by π -radians. FIG. 5

illustrates the vertical alignment of the two sets of interlocked anode vanes or fingers, with the beam intermediate them and the sole 35. From FIG. 6 it can be seen that the two interdigital lines, one comprising terminal disc 39, fingers 38, fingers 40 and disc 41 and the other formed by disc 37, fingers 36, fingers 38 and disc 39, are placed back-to-back so that they are operated in a push-pull manner. Their cavity sections, upper and lower portions of the microwave cavity defined by casing 11 and only partially separated by plate 21, are thereby coupled together so tightly or closely that these two R-F anode sections operate at a single frequency.

Thus, with this arrangement, the length of the interaction region is practically doubled, giving increased power output and efficiency without the drawbacks inherent in lengthening individual fingers. The magnetron structure is geometrically symmetric about the center plane through plate 21; this causes the transition from the TE mode of the interaction region to the TEM mode in the coaxial output to be much smoother, i.e. less frequency sensitive. The coupling to the R-F structure is improved, resulting in a uniform power-frequency response curve, particularly desirable for voltage-tunable magnetrons. A symmetrical output signal in correct phase is provided without the necessity of using transformers. In addition, radiation of leakage R-F power from the ends of the new magnetron device has been eliminated or severely attenuated, whereas conventional magnetrons waste a substantial part of the generated power through leakage losses.

An alternate embodiment of the R-F anode structure is illustrated in FIG. 7, wherein like reference numerals indicate the same parts as in FIGS. 1 and 6. The terminal discs 37, 39, and 41 are the same, as are fingers 38. However, it has been discovered that the alternate fingers need not be separated into two sections. Thus solid fingers 42, intergrally connected at their ends to discs 37 and 41, replace the separate sets of fingers 36 and 40, there now being two sets of fingers. However, effectively two back-to-back interdigital lines are still present, the first comprising the upper parts of fingers 38 and the upper halves of fingers 42, the other including the bottom halves of these fingers. Note that, in the prior embodiment, fingers 36 and 40 were at the same R-F potential, both being connected to the cavity casing.

While ceramic insulating spacers have been shown for electrically isolating and positioning various tube components, it is equally possible to rigidly mount the various electrodes, as by brazing or welding, to support members of the cavity and omit the spacer rings, such as 45, 46, 47, 51 and 54. In this event, the magnetron should be placed in an evacuated microwave cavity. In the embodiment of FIGS. 1 and 6, only the magnetron tube within the spacer rings need be evacuated.

The voltage-tunable magnetron of the present invention thus affords a significant improvement in efficiency, greater power output capability, reduced end radiation losses, and a smoother tuning response characteristic. The physical arrangement of the components features ease of assembly and dis-assembly, so that if a component is faulty it may be quickly and simply replaced. By merely lifting off pole piece 90 and connector 83, disengaging ring nut 30 and removing connector ring 48, a defective magnetron tube can be replaced as a unit in the microwave cavity. Also, the electron discharge device described herein may be employed either as an amplifier or as an oscillator.

It will be apparent that the embodiments shown are only exemplary and that various modifications can be made in construction and arrangement within the scope of the invention as defined in the appended claims.

I claim as my invention:

1. An electron discharge device of the voltage tuneable magnetron type comprising in combination;
  - (a) cavity means,
  - (b) cold cathode means,
  - (c) electron beam injection means disposed at one end of said cold cathode means,
  - (d) means for applying a magnetic field within said cavity means,
  - (e) a cylindrical anode assembly surrounding said cathode means centrally disposed in said cavity means, said anode assembly including a series of axially extending anode fingers, said anode fingers connected to form two sets of said anode fingers, said sets of anode fingers interdigitated with respect to one another,
  - (f) an upper disc, a lower disc, and a central disc,
  - (g) a first set of anode fingers connected to said upper and said lower discs, and the second set of anode fingers connected to said central terminal disc,
  - (h) broad band output means including TEM mode transmission means having an upper ground plane and a lower ground plane, and a centrally disposed conductor, said upper ground plane connected to and surrounding said upper disc, said lower ground plane connected to and surrounding said lower disc, and said centrally disposed conductor connected to and surrounding said central disc.
2. A voltage tuneable magnetron as in claim 1 wherein said electron beam injection means comprises a cone shaped, helically wound filament means, the apex of said filament means being adjacent said cold cathode means.
3. A magnetron as in claim 1 wherein said first set of anode fingers includes a continuous bar extending from said upper disc to said lower disc.
4. An electron discharge device of the voltage tuneable magnetron type comprising in combination;
  - (a) cavity means,
  - (b) cold cathode means,
  - (c) electron beam injection means disposed at one end of said cold cathode means,
  - (d) means for applying a magnetic field within said cavity means,
  - (e) a cylindrical anode assembly surrounding said cathode means centrally disposed in said cavity means, said anode assembly including a series of axially extending anode fingers, said anode fingers connected to form two sets of said anode fingers, said sets of anode fingers interdigitated with respect to one another,
  - (f) an upper disc, a lower disc, and a central disc,
  - (g) a first set of said anode fingers connected to said upper and said lower discs, and the second set of anode fingers connected to said central terminal disc,
  - (h) broad band output means including TEM mode transmission means having an upper ground plane and a lower ground plane, and a centrally disposed conductor, said upper ground plane connected to and surrounding said upper disc, said lower ground plane connected to and surrounding said lower disc, and said centrally disposed conductor connected to and surrounding said central disc, and
  - (i) said first set of anode fingers comprised of one set of fingers extending downward from said upper disc and another set extending upward from said lower disc in axial alignment with said one set of fingers.
